DESIGN FOR AN EYELID PROTECTOR- TURNER-HOLDER

Helen Leyne, New York, N. Y.

Application August 11, 1938, Serial No. 79,277

Term of patent 14 years

To all whom it may concern:

Be it known that I, Helen Leyne, a citizen of the United States and a resident of New York, Borough of Manhattan, in the county and State of New York, United States of America, have invented a new, original, and ornamental Design for an Eyelid Protector-Turner-Holder, of which the following is a specification, reference being had to the accompanying drawing, forming part thereof.

Fig. 1 is a plan view of an eyelid protector-turner-holder, showing my new design.

Fig. 2 is an edge view thereof.

Fig. 3 is a cross sectional view taken on the line 3—3 of Fig. 1 looking toward the arrows.

Fig. 4 is a cross sectional view taken on the line 4—4 of Fig. 1 looking toward the arrows.

I claim:

The ornamental design for an eyelid protector-turner-holder, substantially as shown.

HELEN LEYNE.
